(57) **CLAIM**

The ornamental design for an exhaust system for an agricultural work vehicle, substantially as shown and described.

DESCRIPTION

FIG. 1 is a perspective view of an exhaust system for an agricultural work vehicle showing our new design in use condition mounted to a broken line showing of an agricultural work vehicle which forms no part of the claimed design; FIG. 2 is a perspective view thereof;

FIG. 3 is a left side view thereof;

FIG. 4 is a right side view thereof;

FIG. 5 is a top view thereof;

FIG. 6 is a bottom view thereof;

FIG. 7 is a back view thereof; and,

FIG. 8 is a front view thereof.

Phantom lining, where utilized, is for illustrative purposes only and forms no part of the claimed design.

1 Claim, 7 Drawing Sheets
